SAFETY DEVICE FOR MACHINES SUCH AS
PUNCH PRESSES AND THE LIKEWalter H. Brush, Sea Cliff, Long Island, and
Frank Siezak, Maspeth, Long Island, N. Y.

Application March 18, 1933, Serial No. 661,500

18 Claims. (Cl. 192—129)

Our invention relates to safety devices for machines such as punch presses and the like, which are controlled by an operator and particularly to devices adapted to prevent careless or unrestricted operation of such machines.

Punch presses and machines of this general character are commonly provided with a source of power connected to the machine by a clutch or other means for starting and stopping the machine. The clutch is generally actuated by some manipulative means such as a foot pedal under the control of the operator. In practice, the operator may intentionally or accidentally keep the pedal depressed so that the machine operates continuously while the work is inserted and removed from the machine. The operations are performed with such regularity that the operator tends to become careless and not infrequently fails to remove his hand or a piece of work from the machine in time, and as a result the operator may be injured or the work damaged. The danger of such unrestricted operation of machines such as punch presses has been recognized and in many instances ordinances or laws have been passed requiring the provision in such machines of safety devices which necessitate operation of the foot pedal or other manipulative means separately for each successive operation of the machine.

It has been proposed heretofore to effect this result by means of various electrical connections serving to operate the clutch between the driving element and the machine. Moreover, this result has been attained heretofore by a clutch of special design. However, such devices have not been adapted for easy application to existing machines and have required expensive alterations in the structure of the machine or in the mechanism for controlling the operation of the clutch.

In accordance with our invention, disadvantages and hazards presented by the structures of the prior art are overcome and simple inexpensive means provided for preventing unrestricted or careless operation of the machine. In a preferred form of our invention the usual clutch between the driving element and the machine is employed and any suitable manipulative means, such as a foot pedal or hand lever, or in the event the machine is controlled by electricity, suitable push buttons or switches and solenoids or magnets may be used. In order to prevent continued operation of the machine, we provide a separable connection between the manipulative means and the clutch by means of which the separable members are automatically disconnected upon pre-

determined movement of the machine and are only connected upon the release of the manipulative means. The clutch is thereby released automatically so that movement of the machine is stopped upon completion of each operation and will not again be initiated until the manipulative means is released and again operated.

It is an object of our invention to prevent careless or unrestricted operation of machines such as punch presses and the like, and to provide an attachment adapted to be applied to existing machines of various types and constructions for disconnecting the driving element from the machine upon the completion of a pre-determined operation of the machine.

Another object of our invention is to provide safety mechanism for restricting the operation of a machine adapted to be applied as an attachment to existing machines with a minimum of expense and delay in applying the same.

A further object of our invention is to provide a safety device in the form of a unitary structure the elements of which are so constructed and assembled as to be capable of being applied as a unit directly to the frame of a machine or other support.

A further object is to provide a machine such as a punch press having a safety device adapted to cause the machine to stop upon the completion of each operation.

A further object of our invention is to provide a separable connection between the clutch and the manipulative means for operating the clutch.

A further object of our invention is to provide automatic means for connecting and disconnecting the members of a separable connection between the clutch and manipulative means for machines of the character described.

Another object of our invention is to provide latch mechanism adapted to be released upon the completion of a pre-determined operation of the machine, whereby further operation of the machine is prevented until the latch is again brought into operation by release of the manipulative means.

A further object of our invention is to provide safety mechanism which is simple and inexpensive to construct and operate and which comprises elements capable of withstanding continued and severe usage.

These and other objects and features of our invention will appear from the following description thereof in which reference is made to the accompanying figures of the drawings illus-

trating a preferred embodiment of our invention. In the drawings:

Fig. 1 is a front view of a punch press having a safety device embodying my invention applied thereto.

Fig. 2 is a vertical sectional view through the form of safety device illustrated in Fig. 1 taken on the line 2—2 of Fig. 3 looking in the direction of the arrows.

Fig. 3 is a view of the safety device illustrated in Fig. 1 looking toward the left, with the cover of the device removed and parts broken away to show details of the construction.

Fig. 4 is a view partly in section indicated by the line 4—4 of Fig. 3 looking in the direction of the arrows.

In the form of our invention illustrated in the figures of the drawings, a machine such as a punch press is provided comprising a frame 2 and a reciprocating member or head 4 actuated by a rotatable shaft 6 having a crank, eccentric or other means thereon for operating the connecting rod 8 for moving the reciprocating member up and down. The machine is powered by a driving element 10 such as a pulley or motor, and is provided with clutching means 12 of usual or suitable construction adapted to connect and disconnect the driving element and the machine to operate the same. The clutching means is actuated by pawl 14 or other device operable by manipulative means under the control of the operator. The manipulative means is shown as a foot pedal 16, but may be any other suitable means such as a hand lever, and in the event the machine is electrically controlled, such means may comprise one or more push buttons or switches and associated solenoids, magnets, etc.

In order to prevent careless or continuous operation of the machine we provide a safety device generally designated 18 adapted to be applied to existing machines of standard construction as an attachment although the device may be incorporated in such machines as an integral part thereof if desired. In order to enable the safety device to be quickly and easily applied to existing machines with a minimum of expense and delay we prefer to employ elements and means so constructed and arranged that they may be mounted on a single plate or other supporting means forming a unitary structure that may be easily bolted or otherwise secured to a stationary part of the machine such as the frame or bed.

The safety device is preferably interposed between the manipulative means and the clutch and is so constructed and operated that the manipulative means is disconnected from the clutch upon the completion of an operation or upon predetermined movement of the reciprocating member or other means driven by the machine as an incident to the operation thereof. For this purpose we provide a separable connection between the manipulative means and the clutch comprising a member such as the rod 20 connected to the foot pedal or other manipulative means and a rod or member 22 connected to the pawl 14 or other element of the clutch 12.

The safety device shown at 18 in Fig. 1 is located in a suitable casing adapted to be attached as a unit to the frame of the machine or other support and serves automatically to connect and disconnect the numbers 20 and 22 connected to the manipulative means and clutch respectively. In the preferred form of the device illustrated a supporting plate 24 may be provided

preferably secured directly to the frame 2 by means of bolts 26 and provided with a removable cover 31 shown in dotted lines in Fig. 2. Bearings 30, 32 and 34 are rigidly secured to the plate 24 by bolts 35 or may be formed integral with the plate if desired.

An actuating element 36 is slidably mounted in the bearings 30 and 32 and is connected to the manipulative means by the rod or cable 20, one end of which is connected to an eye bolt 38 carried by the actuating element as shown, a spring 40 surrounds the element 36 and bears against the upper portion of the bearing 30 and against a shoulder 42 on the actuating element, serving to urge said element upward and to hold the member 20 and foot pedal 16 in raised position. Upward movement of the element 36 is limited by any suitable means such as the collar 44 carried by said element and engaging the lower face of the bearing 30.

The upper end of the actuating element 36 is slidable within the bearing 32 and is formed with a central opening within which a clutch releasing element is longitudinally movable. A spring 48 shown in Fig. 1 urges the releasing element upward to separate said element from the actuating element whereby the clutch is disconnected from the manipulative means. Upward movement of the releasing element is limited by any suitable means such as a stop 50 carried thereby and adapted to engage a stop 52 mounted in the bearing 32 and projecting through a slot 54 in the actuating element 36. The lower portion of the releasing element may be formed with transversely projecting lugs 56. As shown these lugs are formed on a pin carried by the lower portion of the releasing element and held in fixed position by the set screw 57 with the lugs extending laterally through the slots 58 in the actuating element. The lugs 56 are formed with upwardly facing engaging surfaces 60 and lower cam surfaces 62.

A latch carrying member 64 is shown as secured to the actuating element by screws 65 and is provided with latches 66 positioned to engage the lugs 56 on the releasing element. These latches serve to connect the releasing element to the actuating element so that movement of the actuating element under the control of the manipulative means is transmitted to the releasing element and the clutch so that the clutch is operated to set the machine in motion. The latch carrying member 64 is movable transversely of the actuating element upon the studs 68 and 70 carried by said element and projecting through openings in the latch carrying member. A spring 72 surrounds the stud 68 and urges the latch carrying member and the latches to the right, as shown in Fig. 3, so that the latches snap into connecting position above the projecting lugs 56 when the elements 36 and 48 are moved to their connecting positions, as shown in Figs. 2 and 3. The upper surfaces of latches 66 are inclined and adapted to slide along the lower cam surfaces 62 of the lugs 56 upon upward movement of the actuating element under the influence of spring 40 when the manipulative means is released. The latch carrying element is moved to the left, as shown in Fig. 3, by the cam surfaces 62, permitting the actuating element to move upwardly until the latches are raised above the lugs 56 and into position to snap into connecting engagement therewith.

In order to disconnect the elements 36 and 75

46 and to disconnect the members 20 and 22 connected to said elements so that the clutch 12 is disengaged, the safety device is provided with a tripping element 74 slideable in the bearing 34 on the plate 24. The tripping element is shown as provided with a cam surface 76 movable into engagement with a projection 78 on the latch carrying member. Normally, the trip 74 is held in its lowered position by a spring 80 and the cam surface 76 is located sufficiently below the projection 78 to permit downward movement of the actuating element and the latch carrying member upon operation of the manipulative means without bringing the projection 78 into effective engagement with the cam surface 76. For this purpose, the trip may be provided with a dwell 81 above the cam surface against which the projection 78 normally bears.

Upward movement of the tripping element against the action of the spring 80 brings the cam surface 76 into engagement with the projection 78, shifting the latch carrying member and the latches 66 to the left, (see Fig. 3), so that the releasing member 46 may be moved upwardly by the spring 48, disconnecting the member 22 from the member 20, causing disengagement of the clutch 12 so that the machine is stopped. Movement of the tripping element may be effected by any suitable means such as connections from the reciprocating member or the connecting rod 8 or other means driven by the machine as an incident to the operation thereof. As illustrated in the drawings, a cable 82 is provided which is connected at 84 to the connecting rod. The cable passes over the pulleys 86 and 88 mounted on the frame and the opposite end thereof is connected to an eye bolt or other connecting means 90 on the tripping element 74 to move the trip upwardly upon completion of an operation or in response to a pre-determined movement of the reciprocating head and connecting rod. The connection between the reciprocating member and the tripping element preferably is such that the trip is not raised until the head 4 has descended to substantially the lower limit of its movement. Upon operation of the tripping element, the clutch and manipulative means are disconnected and the releasing element and lugs 56 are raised above the latches 66 so that the connection remains broken until the manipulative means is released and the member 20 and actuating element 36 raised by the spring 44 to bring the latches 66 above the lugs 56 so that the latches may again snap into engaging position above the lugs 56 to connect the clutch and manipulative means preparatory to a succeeding operation.

With the construction described above, the machine is set into operation by depressing the pedal 16, which moves the member 20 and actuating element 36 downward. The latches 66 of the latching element 64, being in engagement with the lugs 56 on the releasing element, move the releasing element and the member 22 downward, actuating the pawl 14 to cause engagement of the clutch 12 so as to connect the driving element 10 to the shaft 6, whereby the shaft is rotated and the reciprocating member 4 is moved downward to perform an operation. As the reciprocating member moves downward and approaches the lower limit of its movement, the cable 82 becomes taut, and as the reciprocating member continues to move, the cable pulls the tripping element 74 upward against the action of the spring 80, bringing the cam surface 76 into engagement with the

projection 78 on the latch carrying member. This member is then moved to the left, as shown in Fig. 3, against the action of the spring 72, moving the latches out of engagement with the lugs 56 on the releasing element. The spring 48 then moves the member 22 and the releasing element upward so that subsequent movement of the reciprocating head into position to permit the tripping element to move downward and allow the latch carrying member to again move to the right will not result in connecting the releasing element to the actuating element. It is then necessary to release the manipulative means before the machine can be further operated. Upon release of the manipulative means, the actuating element 15 is raised by the spring 40 and the upper faces of the latches 66 engage the lower cam surfaces 62 of the lugs 56. As the actuating element and latch carrying member continue to move upward, the latches slide along the surface 62 until in position to snap into engagement with the upper surfaces 60 of the lugs so as to again connect the releasing element to the actuating element, whereby the member 20 connected to the manipulative means is connected to the member 22 connected to the latch. The device is then in position to permit another operation of the machine.

While our invention has been shown and described as applied to punch presses, and a preferred form of safety device adapted to be applied to existing machines has been shown and described by way of illustration, it will be apparent that our invention is adapted for use in connection with other machines and apparatus and the form and construction of the safety device may be materially changed without departing from the spirit and scope of our invention.

What is claimed is:—

1. In a machine having a driving element, mechanism for connecting the driving element to the machine, and manipulative means for actuating said mechanism, a safety device comprising means adapted to be interposed between the manipulative means and said mechanism to connect the same, and an element actuated by the machine as an incident to its operation serving to disconnect said manipulative means from said mechanism to cause stopping of the machine.

2. In a machine having a driving element, a clutch for connecting the driving element to the machine, and manipulative means for actuating said clutch, a safety device comprising a latch interposed between said manipulative means and said clutch serving to connect the same, and means actuated by the machine as an incident to its operation to release said latch and disconnect said manipulative means from the clutch to cause stopping of the machine.

3. In a machine such as a punch press, having a driving element, a clutch and manipulative means for actuating said clutch to connect said driving element to the machine to operate the same, a safety device comprising a latch interposed between said clutch and said manipulative means for connecting the same, a tripping element movable to release said latch and disconnect said manipulative means from said clutch, and means operable by the machine upon a pre-determined movement thereof for actuating said tripping element to disconnect said clutch and manipulative means and cause said machine to stop.

4. In a punch press or the like, having a driving element, clutching means for connecting the driving element to the machine to operate the

same, manipulative means, and means for connecting said manipulative means to said clutching means, a safety device being connected into and forming a part of said connecting means 5 and comprising a support, an actuating element supported thereby and connected to said manipulative means, a releasing element connected to said clutching means, a latch connecting said actuating element and releasing element, and 10 means driven by the machine as an incident to an operation thereof for releasing said latch.

5. In a machine having a clutch and manipulative means therefor, a safety device comprising separable members for connecting said manipulative means to the clutch and means for connecting and disconnecting said members including an actuating element, a releasing element, a latch carried by one of said elements adapted to engage the other element, and means 20 actuated by the machine as an incident to its operation serving to disengage said latch from said other element.

6. In a machine having a clutch movable to effect operation of the machine and manipulative means for actuating said clutch, a safety device comprising separable members for connecting said manipulative means to said clutch, means operable upon release of said manipulative means for connecting said separable members, and means movable to disconnect said separable members upon completion of a pre-determined operation of said machine.

7. In a machine such as a punch press or the like having a clutch, manipulative means for the clutch, and a connection between the clutch and manipulative means, a safety device comprising an element connected to the clutch and forming a part of the connection between the clutch and manipulative means, a second element connected to the manipulative means and forming a part of the connection between the clutch and manipulative means, a latch carried by one element and engaging the other element, means for urging said latch into engagement with said other elements whereby movement of the members into a pre-determined position automatically connects the same, a tripping element actuated by the machine movable to disengage said latch from said other elements, and means for urging 50 said elements apart whereby release of said latch causes said elements to be separated.

8. In a power press comprising a clutch and manipulative means therefor, a safety device for connecting said manipulative means to said clutch comprising relatively movable elements positioned adjacent each other, connecting means carried by one element and adapted to engage the other element, means for resiliently urging said connecting means into engagement 60 with said other element and means actuated by the machine for moving said connecting means out of engagement with said other element.

9. In a power press a clutch and manipulative means therefor, an element connected to said manipulative means, a second element connected to said clutch, a latch carried by one of said elements and urged into engagement with the other element to connect said manipulative means to said clutch and a tripping element actuated by the machine to disengage the latch from the other element.

10. In a punch press or other machine having a clutch and manipulative means therefor, a safety device comprising members connected to 75 said manipulative means and clutch respectively,

a unitary structure comprising a plate adapted to be secured to the frame of the machine and having elements supported thereon for connecting and disconnecting said members and means actuated by the machine as an incident to its operation to effect movement of said elements to disconnect said members to cause stopping of the machine.

11. A device for controlling the operation of a machine such as a punch press or the like comprising a driving element, mechanism for connecting the driving element to the machine to operate the same, manipulative means for actuating said mechanism, means interposed between said manipulative means and said mechanism serving to connect the same, and a tripping element actuated by the machine upon a pre-determined performance thereof to disconnect said manipulative means from said mechanism to cause stopping of the machine.

12. A device for controlling the operation of a machine such as a punch press or the like comprising a driving element, clutch mechanism for connecting the driving element to the machine to operate the same, manipulative means for actuating said clutch mechanism, a latch interposed between the said manipulative means and said clutch mechanism serving to connect the same, and a tripping element actuated by the machine upon a pre-determined performance thereof to release said latch and disconnect the manipulative means from said clutch mechanism to cause stopping of the machine.

13. A device for controlling the operation of a machine such as a punch press or the like comprising a driving element, clutch mechanism for connecting the driving element to the machine to operate the same, manipulative means for actuating said clutch mechanism, a separable connection between said manipulative means and the clutch mechanism, a latch for connecting the separable members of said connection, and a tripping element actuated by the machine upon the performance of a single operation thereof to release said latch whereby said members are separated and said manipulative means is disconnected from said clutch mechanism.

14. A device for controlling the operation of a machine such as a punch press or the like comprising a driving element, clutch mechanism for connecting the driving element to the machine to operate the same, manipulative means for actuating said clutch mechanism, a separable connection between said manipulative means and the clutch mechanism, a latch for connecting the separable members of said connection serving to connect said members upon release of said manipulative means, and a tripping element actuated by the machine upon the performance of a single operation thereof to release said latch whereby said members are separated and said manipulative means is disconnected from said clutch mechanism.

15. In combination with a punch press or the like, a reciprocating member, a driving element, mechanism for connecting the driving element to the reciprocating element, manipulative means for actuating said mechanism, means interposed between said manipulative means and said mechanism serving to connect the same, a tripping element and means actuated by said reciprocating member to operate said tripping element to disconnect said manipulative means from said mechanism.

16. In combination with a punch press or the

like, a reciprocating member, a driving element, a clutch mechanism for connecting the driving element to the reciprocating element, manipulative means for actuating said clutch mechanism, a latch interposed between said manipulative means and said clutch mechanism serving to connect the same, a tripping element for said latch and means actuated by said reciprocating member to operate said tripping element and release said latch to disconnect the manipulative means from the clutch mechanism.

17. In a machine such as a punch press, a reciprocating member, a driving element, a clutch for connecting said driving element to said reciprocating member, manipulative means for actuating said clutch and means for connecting and disconnecting said manipulative means and clutch to prevent unrestricted operation of said reciprocating member comprising separable members connected to said manipulative means and said clutch respectively, an actuating element connected to one of said separable members, a releasing element connected to the other of said separable members and positioned adjacent said actuating element, a latch carried by said actuating element and movable relative thereto into engagement with the releasing element to connect said members and a tripping element connected to the reciprocating member and movable upon the completion of a pre-determined operation thereof to move

said latch out of engagement with said releasing element to disconnect said elements and cause stopping of the machine.

18. In a machine such as a punch press, a reciprocating member, a driving element, a clutch for connecting said driving element to said reciprocating member, manipulative means for actuating said clutch and means for connecting and disconnecting said manipulative means and clutch to prevent continued operation of said reciprocating member, comprising separable members connected to said manipulative means and said clutch respectively, an actuating element connected to one of said separable members, a releasing element connected to the other of said separable members and positioned adjacent the actuating element, a latch carried by said actuating element and movable relative thereto into engagement with the releasing element to connect said elements, a spring for urging said latch into engagement with said releasing element and a tripping element connected to the reciprocating member and movable upon the completion of a pre-determined operation thereof to remove said latch from engagement with said releasing element against the action of said spring to disconnect said elements and cause stopping of the machine.
